HANS REIHLLEN, OF KARLSRUHE, BADEN, GERMANY, ASSIGNOR TO MILTON M. ADLER,
OF NEWARK, NEW JERSEY.

DETONATING FIREWORK.

Application filed September 21, 1927. Serial No. 220,897.

This invention relates to improvements in detonating fireworks or pyrotechnic devices known to the industry and trade as "grass-hoppers"; and the invention has for its object to provide a novel construction of such form of firework as well as a novel method of producing the same.

In the manufacture of the form of fireworks known as "grass-hoppers" as heretofore carried on, a train of loose gun powder is laid on a sheet of paper and the latter is then first folded longitudinally upon itself around and so as to enclose the powder train, and then the longitudinally folded wrapper is folded transversely back and forth upon itself to produce a series of connected sections, in each of which is contained a proportion of the gun-powder loosely spread therethrough. When thus folded the wrapper is encircled transversely with a flexible tie of cord or the like to hold the sections against opening out. When the device thus made is ignited at one end, the powder train is expected to burn from end to end, and to produce, as combustion thereof takes place in each section within which it is confined, a series of reports or detonations as the combustion proceeds from section to section of the device. Owing to the fact that the powder is loosely disposed within the sections and around the bends or folds subdividing one section from another, it frequently occurs especially in handling the devices during shipment and during sales thereof, that the loose powder will shift away from one end or the other of said sections, and out of the bends or folds between the sections, with the consequence that the powder train becomes interrupted, and when the device is ignited combustion will fail to carry over from one section to the other so that the desired succession of reports or detonations is not obtained, and the user is both disappointed and dissatisfied.

It is the principal object of this invention to provide a novel construction of firework of the "grass-hopper" type, which avoids the failures above referred to and which may be transported and handled without risk of injury to its normal operative condition; and, furthermore, to provide a construction in which the distribution and disposition of its powder content is such that maximum detonating effect is assured upon combustion thereof within each section of the device, while at the same time also assuring the carry-

ing of combustion around the folds or bends intermediate the sections without interruption and in such manner as to slow down the combustion between sections sufficiently to assure the desired succession of reports or detonations.

The invention also has for an object to provide a novel method of manufacturing "grass-hopper" firework devices to procure the novel construction hereinafter described.

The invention is clearly illustrated in the accompanying drawings, in which:

Figure 1 is a perspective view of a firework device of the type known as a "grass-hopper", the same being constructed in accordance with the principles of this invention; Figure 2 is a longitudinal section through the completed device as made according to this invention; Figure 3 is a view of the wick element of the device; Figure 4 is another view of the wick element after dry gun powder is applied thereto; Figure 5 is a perspective view of the wick inserted in a tubular wrapper or casing prior to folding the latter upon itself to produce the series of explosive sections; Figure 6 is a view showing the starting fold of the wrapper or casing; and Figure 7 is a fragmentary longitudinal section through a completed fold subdividing adjacent sections of the device.

Similar characters of reference are employed in all of the hereinabove described views, to indicate corresponding parts.

Referring now to said drawings, the reference character 1 indicates a wick. This wick is preferably made of twisted fibrous material, such as cotton, jute, or the like; or the same may be made of any other material found to be suitable for the purpose. The wick 1 is first more or less saturated in a suspended solution of gum arabic and gun powder, the latter preferably being of that grade known as "meal" powder. While the thus more or less saturated wick is still moist, it is rolled in dry "meal" gun powder, to thereby cause the latter to adhere to the exterior surfaces of the wick, so that a coating or encrustation 2 of dry gun-powder is deposited on said wick, as illustrated in Figure 4 of the drawings.

The reference character 3 indicates a casing preferably made of paper. It is preferable to provide said casing 3 in the form of an elongated tube within which the prepared wick is inserted while its body is still moist.

with the gum arabic-gun powder solution, whereupon the tubular casing 3 is flattened down upon the wick enclosed therein, as shown in Figure 5 of the drawings. While it is preferred to employ the paper casing in initial tubular form as above stated, this is not absolutely essential, since a flat paper sheet may be used and folded longitudinally upon itself around the wick, to produce the flattened tubular wrapper characteristic of the "grass-hopper" firework device.

After the prepared wick is thus inserted in the flattened tubular casing 3, the latter is transversely folded back and forth upon itself in zig-zag fashion to provide a series of connected sections 3' of desired number and desired individual length (see Figures 1 and 2).

The making of the transverse folds 3'' in the wrapper or casing 3 (which may be done either by hand or by machine) exerts a squeezing or compacting pressure upon the portions of the dry powder encrusted wick which are disposed at and adjacent to the line of fold, whereby the dry adhering powder at the wick portions experiencing such pressure is forced into a more compact and intimate union with the underlying moist gum arabic-gun powder mixture in the more or less saturated wick body, with the result that a relatively slow burning section or link 4 is produced extending around each fold 3'' between adjoining sections 3', while within each section 3' intermediate the folds 3'' the dry adhering powder on the portions of wick extending therethrough is left relatively free and uncompressed so as to be capable of comparatively rapid combustion within the confined interior spaces of the sections 3', and consequently, when ignited, the rapid expansion of the gases of combustion within the confined space of the section interiors will burst the walls thereof with a loud report or detonation. The wick-sections or links 4 will burn with a relatively slow but nevertheless sure combustion, and will serve to carry an igniting spark around the folds 3'' from an exploded section to the next adjacent section, wherein combustion again becomes rapid with desired detonating effect. Thus the complete device when ignited at one end will progressively burn from section to section toward the other end, and in the course of combustion will produce a series of successive explosions, upon the occurrence of each of which the device as a whole will jump about, from which action the name "grass-hopper" is derived.

After the casing is folded to produce the body comprising the series of connected sections 3', said body is wrapped transversely with a retaining tie 5 of cord or the like, to retain the sections against separation from folded relation both during handling of the same, and during the detonation thereof.

In order to provide a convenient point for initial ignition of the device, one end of the wick 1 is allowed to project exteriorly from an end section 3' of the device, and this free end of the wick is dipped in a strong solution of gum arabic and gun-powder to form therefrom a comparatively slow burning igniting fuse 6. It will be obvious, however, that an independent fuse of any other desired form may be inserted in the free end of an end section 3' of the device to serve as an igniting fuse, if such arrangement is preferred.

As many changes could be made in the above described construction and many different embodiments of this invention could be made without departing from the scope thereof, it is intended that all matter contained in the above description or shown in the accompanying drawings shall be interpreted as illustrative and not in a limiting sense.

Having thus described my invention, I claim:

1. A firework device of the kind described, comprising a tubular casing folded transversely upon itself to provide a plurality of connected sections, and a body having its surfaces encrusted with gun-powder extending through said casing from section to section.

2. A firework device of the kind described, comprising a tubular casing folded transversely upon itself to provide a plurality of connected sections, a fibrous body more or less saturated with a solution of gum arabic and gun-powder disposed to extend through said casing from section to section, and portions of said body within each section having its surfaces encrusted with dry gun powder.

3. A firework device of the kind described, comprising a tubular casing folded transversely upon itself to provide a plurality of connected sections, a fibrous body more or less saturated with a solution of gum arabic and gun powder disposed to extend through said casing from section to section, portions of said body within each section having its surfaces encrusted with dry gun powder, means to retain said casing in folded condition, and means to ignite said fibrous body at one end thereof.

4. A firework device of the kind described, comprising a tubular casing, a fibrous body treated with gum arabic and gun powder extending through said casing, said casing being folded transversely upon itself to provide a series of connected sections, and said fibrous body having its gum arabic-gun powder content compacted by the pressure of the casing at and adjacent to the lines of fold of the latter to produce at such points comparatively slow burning body portions intermediate the relatively rapid burning portions lying within the casing sections.

5. A firework device of the kind described, comprising a tubular casing, a fibrous body

treated with gum arabic and gunpowder extending through said casing, said casing being folded transversely upon itself to provide a series of connected sections, and said fibrous body having its gum arabic-gun powder content compacted by the pressure of the casing at and adjacent to the lines of fold of the latter to produce at such points comparatively slow burning body portions intermediate the 10 relatively rapid burning portions lying within the casing section, means to retain said casing in folded condition, and said fibrous body having an exteriorly projecting end portion treated to provide an igniting 15 fuse.

6. The method of producing firework devices of the kind described, comprising saturating more or less a fibrous wick in a solution of gum arabic and gun powder, rolling the wick while moistened by said solution in dry gun powder to encrust the surfaces of the wick therewith, inserting the wick thus treated in an enveloping wrapper, and then folding said wrapper transversely upon 20 itself to produce a series of connected sections enclosing rapidly combustible gun powder encrusted portions of said wick, and whereby the folding of said wrapper compresses the dry gun powder into the underlying gum arabic-gun powder solution in those portions of the wick at and adjacent to the folds to there-

25

30

by produce comparatively slow burning portions intermediate each wrapper section.

7. The method of producing firework devices of the kind described, comprising saturating more or less a fibrous wick in a solution of gum arabic and gun powder, rolling the wick while moistened by said solution in dry gun powder to encrust the surfaces of the wick therewith, inserting the wick thus 40 treated in an enveloping wrapper, and then folding said wrapper transversely upon itself to produce a series of connected sections enclosing rapidly combustible gun powder 45 encrusted portions of said wick, and whereby the folding of said wrapper compresses the dry gun powder into the underlying gum arabic-gun powder solution in those portions of the wick at and adjacent to the folds to thereby produce comparatively slow burning 50 portions intermediate each wrapper section, providing at an end section of the wrapper an exteriorly projecting end of said wick body, and impregnating said exterior wick end with a solution of gum arabic and gun-powder to 55 produce a relatively slow burning igniting fuse.

In testimony, that I claim the invention set forth above I have hereunto set my hand this 15th day of September 1927.

HANS REIHLEN.
